UNITED STATES PATENT OFFICE

GUSTAV C. PEARSON, OF DENVER, COLORADO, ASSIGNOR TO GARDNER-DENVER COMPANY, OF DENVER, COLORADO, A CORPORATION OF DELAWARE

TOOL HOLDER

Application filed April 19, 1928. Serial No. 271,383.

The present invention relates to tool retainers for rock drills and the like, the object being to provide a novel and simple structure in which the means for holding the 5 retainer in its operative position and in its inoperative position is simple, is very completely housed and adds practically nothing to the size of the structure beyond that of the retainer mechanism proper.

10 In the accompanying drawings:

Figure 1 is a front elevation of the preferred embodiment of the invention.

Figure 2 is a sectional view on the line 2-2 of Figure 1, and showing the tool 15 retainer in its operative position.

Figure 3 is a view taken on the same plane as Figure 1, but showing the retainer in its inoperative position.

Figure 4 is a view in elevation of the rock 20 shaft with the plunger therein.

Figure 5 is a detail perspective view of said plunger.

In the embodiment disclosed, the holder for the tool is designated generally by the 25 reference numeral 6 and is designed to receive a steel 7 having a collar 8. The holder includes a housing 9 having a transverse enlargement 10 at its front end provided with a bore 11. In this bore is journaled a rock 30 shaft 12 having its ends projecting beyond the enlargement 10 and provided with transverse openings 13. A tool-retaining yoke 14 is provided with S-shaped side arms 15, the ends of which pass through the openings 13 35 of the shaft 12, and are pinned therein as indicated at 16. The portions of the side arms above the shaft 12 are adapted to abut against stop lugs 17 formed upon the opposite sides 40 of the housing 9.

The rock shaft 12 is provided centrally 45 with a transverse socket 18 opening through one side and in said socket is a reciprocatory plunger 19 chambered to receive a coiled spring 20 located in said socket and bearing against the bottom thereof and against the plunger to urge the same outwardly. A toggle link 21 is interposed between the plunger 19 and the adjacent wall of the bore 11, said 50 toggle link being provided with curved heads

22 located in sockets 23 formed in the plunger 19 and wall of the bore.

The arrangement is such that when the yoke is in its operative position, as shown in Figure 2, with its front portion in the path 55 of the collar 8 of the drill steel 7, the toggle link 21 is in a position to cause the spring to urge said shaft in a direction to hold the yoke in said operative position. To move the yoke to its inoperative position, it is only 60 necessary to swing the same rearwardly, thereby turning the rock shaft until the toggle link 21 has moved past its dead center, whereupon the spring will react and hold 65 said yoke in the position shown in Figure 3.

From the foregoing, it is thought that the construction, operation and many advantages of the herein described invention will be apparent to those skilled in the art, without further description, and it will be understood 70 that various changes in the size, shape, proportion and minor details of construction may be resorted to without departing from the spirit or sacrificing any of the advantages 75 of the invention.

What I claim is:

1. The combination with a tool holder, of a tool retainer pivotally mounted thereon, a yielding plunger mounted on and having a swinging movement with the retainer, and 80 a toggle link having a bearing against the plunger and against a fixed portion of the tool holder.

2. The combination with a tool holder, of a tool retainer comprising a rock shaft journaled on the tool holder and a yoke having side arms connected to the rock shaft, a yielding plunger mounted in the rock shaft, and 85 a toggle link having a bearing against the plunger and against a portion of the tool 90 holder.

3. The combination with a tool holder including a housing having a transverse bore, of a rock shaft journaled in the bore and projecting from the opposite ends thereof, said shaft having a transverse socket between its ends and within the bore, a retaining yoke having side arms mounted in the projecting ends of the shaft, a spring pressed plunger 95 in the socket of the shaft, and a toggle link 100

bearing against the plunger and against the adjacent wall of the bore.

4. The combination with a tool holder including a housing having a transverse bore, of a rock shaft journaled in the bore, a swinging tool retainer fixed to the rock shaft and causing it to turn, said rock shaft having a transverse socket within the bore, a spring pressed plunger mounted in the rock shaft, and a toggle link that extends into the socket and bears against the plunger and against the wall of the bore, said toggle link having a swinging movement in the shaft socket.

In testimony whereof, I affix my signature.

15 GUSTAV C. PEARSON.
